FOOD GRINDER

Henry J. Talge and John E. Snell, Kansas City, Mo., as signors to John C. Hockery, Kansas City, Mo., as trustee

Application April 4, 1955, Serial No. 35,359

Term of patent 14 years

(Cl. D89—1)

Fig. 1 is a top plan view of a food grinder embodying our new design;

Fig. 2 is a front elevational view of same; and

Fig. 3 is a side elevational view of same.

The essential features of our design reside in the portions shown in full lines.

We claim:

The ornamental design for a food grinder, as shown and described.
